THERMOSTAT CONTROLLED VALVE

Carl N. Shipman and Roy P. Grissom, Oklahoma City, Okla.; said Shipman assignor of sixteen and two-thirds per cent to R. G. Lett and sixteen and two-thirds per cent to Dan C. Paxton, both of Oklahoma City, Okla.

Application May 29, 1940, Serial No. 337,924

1 Claim. (Cl. 277—21)

This invention relates to thermostat controlled valves and has for an object to provide a device of this character particularly adapted for automatic fire sprinkler control.

Ordinarily, when a fire raises the temperature of a building protected by a sprinkler system, the sprinkler head operates continuously to flood the building with water until the arrival of the fire department. With this in mind it is an object of the present invention to provide a simplified form of thermostat controlled valve which may be used as an individual control valve for each separate sprinkler head and will automatically cut off the water supply from the operating sprinkler head when the temperature has decreased below the danger point and thus prevent needless flooding of the building with water.

A further object is to provide a device of this character which will be positive in operation and which will always be in operative position under severe conditions of service.

A further object is to provide apparatus of this character which will be formed of a few strong, simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming a part of this specification:

The figure is a longitudinal sectional view of a thermostat controlled valve constructed in accordance with the invention and showing an alarm device diagrammatically.

Referring now to the drawing in which like characters of reference designate similar parts in the various views, 10 designates a main valve casting having a lined sprinkler head and inlet pipes 11 and 12 connected thereto. A cylinder 13 is mounted upon the open top of the main valve housing and a piston 14 is mounted to move vertically in the cylinder. The piston is provided with a stem 15 which projects through a stuffing box 16 carried by the bottom head 17 of the cylinder and is terminally equipped with a disk valve 18 which seats on a horizontally disposed seat 19 and closes downwardly in the direction of flow through the valve housing 10. A helical compression spring 20 is sleeved on the stem 15 and

bears against the valve 18 and against the bottom head 17 of the cylinder to hold the valve seated.

A cylinder valve housing 21 is disposed adjacent to one side of the cylinder 13 and is connected to the cylinder 13 below the piston 14 by a pipe 22. A valve seat 23 is formed in the housing 21 at the bottom of the pipe 22 and a needle valve 24 is mounted to seat upwardly in the valve seat 23. The needle valve is equipped with a stem 25 which projects through the bottom closure cap 26 of the cylindrical valve housing and a helical compression spring 27 is sleeved on the valve stem and tends to constantly hold the needle valve closed.

A by-pass pipe 28 is connected to the valve housing 10 on the inlet side thereof and is connected to the cylindrical valve housing 21 below the valve seat 23 to permit fluid to pass into the cylinder 13 below the piston 14 through the pipe 22 when the needle valve 24 is opened.

A push rod 29 is engaged through the top closure cap 30 of the cylindrical housing 21 and loosely engages a guide shoulder 32 which projects inwardly from the top of the housing. The lower end of the push rod abuts the top of the needle valve 24 which latter, when seated, projects slightly above the valve seat 23. The push rod is provided axially with a vent opening 33 which opens through the top of the push rod through an enlarged recess 34 and opens through the side of the push rod through a laterally directed branch opening 35.

A thermostat 36 of the bellows type is mounted on a bracket arm 37 which is secured to the top head 38 of the cylinder 13 by screws 39, or other connectors, laterally of a vent opening 40 in the cylinder head 38. The thermostat is provided at the bottom with a stem 41 which is equipped with a rubber disk valve 42. The valve is secured to the lower end of the stem by a screw 43, or other connector, and is adapted to seal the upper end of the vent opening 33 when the thermostat expands.

A tubular collar 44 is snugly sleeved on the stem 41 and is fixedly connected at the upper end to the stem by a pin 45.

A block of insulation 46 is fixed to one side of the tubular collar 44 in any preferred manner and a switch contact 47 is secured to the block by a screw 48. A grounded switch contact 49 is secured to the tubular valve housing 21 to cooperate with the switch contact 47 in controlling a signal circuit 50 to a buzzer 51 which is connected to a battery 52.

In operation, when temperature rises to a danger point as in the case of fire, the thermostat 36 will expand and move the stem 41 downwardly, first until the valve 42 seals the vent 33 and subsequently moves the push rod 29 downward to open the needle valve 24. When the needle valve 24 is open fluid pressure through the by-pass pipe 28 flows past the needle valve into the cylinder 13 underneath the piston 14 and opens the valve 18 to permit flow through the valve casing 10. Simultaneously therewith the switch contacts 47 and 49 are moved into circuit closing position and the buzzer 51 is energized. When the temperature returns to normal, or at least becomes lower than the danger point, the thermostat 36 will contract and lift the stem 41 to open the valve 42 and permit the spring 27 to close the needle valve 24 thereby returning the push rod to normal position. Liquid in the cylinder 13 below the piston 14 then escapes through the pipe 22 and air vent 33 past the open valve 42 and downward inside the tubular collar 44 where it wastes over the top of the tubular valve housing 21. The spring 20 then moves the piston 14 to neutral position and closes the disk valve 18, the vent opening 40 preventing any vacuum in the top of the cylinder 13.

From the above description it is thought that the construction and operation of the invention will be fully understood without further explanation.

What is claimed is:

A pilot valve comprising a cylindrical housing, a pipe entering the housing adapted for connection with a main valve, a valve seat in the housing below the pipe, a spring pressed needle valve 5 in the seat projecting above the seat and closing upwardly, a by-pass pipe entering the housing adapted for connection with the intake side of a main valve permitting fluid to pass into the housing and out through the first named pipe when the needle valve is open, a push rod slidably mounted in the housing and abutting the top of the needle valve, there being an axial vent 10 in the push rod opening through the top of the push rod and through the side of the push rod, a stem disposed above the top of the housing adapted to operate the push rod, a valve on the stem adapted to close the vent opening in the top of the push rod when the push rod is moved by the stem to open the needle valve, retrograde movement of the stem to initial position moving the stem valve to open the vent in the top of the push rod and permitting the spring of the needle valve to close the needle valve, fluid being vented through the first named pipe and through the axial vent in the push rod when the needle valve 15 is closed and the stem valve is open, and a tubular collar on said stem loosely overlapping the upper end of the push rod adapted to direct waste fluid from the axial vent to the exterior of the housing.
